[57] CLAIM

The ornamental design for a vented number plate, as shown and described.

DESCRIPTION

FIG. 1 is a front elevational view of a vented number plate, showing my new design;

FIG. 2 is a rear elevational view thereof;

FIG. 3 is a top plan view thereof;

FIG. 4 is a bottom plan view thereof.

The characteristic feature of the design is the specific pattern of slots arranged along the uppermost and lowermost portions of the number plate.

FIG. 1.

FIG. 2.

FIG. 5.

FIG. 3.

FIG. 4.
